Mitchell M Musial, Esq.

(57) CLAIM

The ornamental design for a baby garment with grips, as shown and described.

DESCRIPTION

FIG. 1 is a front view of a baby garment with grips showing my new design; and,

FIG. 2 is a rear view thereof.

The broken lines represent the portions of the baby garment with grips, which form no part of the claimed design.

1 Claim, 1 Drawing Sheet
